UNITED STATES PATENT OFFICE.

AUGUSTUS F. HARTER, OF CHICAGO, ILLINOIS, ASSIGNOR TO CRIBBEN & SEXTON COMPANY, OF CHICAGO, ILLINOIS, A CORPORATION OF ILLINOIS.

DESIGN FOR A COOKING-RANGE.

42,800.

Specification for Design.

Patented July 16, 1912.

Application filed April 22, 1912. Serial No. 692,537. Term of patent 7 years.

To all whom it may concern:

Be it known that I, AUGUSTUS F. HARTER, a citizen of the United States, residing at Chicago, in the county of Cook, State of Illinois, have invented a new, original, and ornamental Design for a Cooking-Range, of which the following is a specification, reference being had to the accompanying drawing, forming part thereof.

The figure is a perspective view of a cooking range, showing my new design.

I claim:

The ornamental design for a cooking range, as shown.

AUGUSTUS F. HARTER.

Witnesses:

LOUIS P. LARSEN,
WILLIAM J. NOBLETT.
